DESIGN FOR A CURTAIN

Hugo Geller, New York, N. Y., assignor to Pat-chogue-Plymouth Mills Corporation, New York, N. Y., a corporation of New York

Application August 27, 1934, Serial No. 53,085

Term of patent 14 years

To all whom it may concern:

Be it known that I, Hugo Geller, a citizen of the United States, residing in the Borough of Manhattan, county of New York, and State of New York, have invented a new, original, and ornamental Design for a Curtain, of which the following is a specification, reference being had to the accompanying drawing, forming part thereof.

Fig. 1 is a plan view of a curtain showing my design; and

Fig. 2 is an end view thereof.

The rows of eyelets are woven as a part of the

pattern, the lowermost row of eyelets being woven in the body of the curtain of relatively open or plain lace network, and the middle and uppermost rows of eyelets are formed in strips or bands of relatively close or finely woven lace. The curtain fabric between the uppermost and middle rows of eyelets is of relatively open or plain lace network, the same as the body of the curtain.

What is claimed is:

The ornamental design for a curtain as shown and described.

HUGO GELLER.
